United States Patent Office.

EDWARD Q. NORTON, OF BANGOR, MAINE, ASSIGNOR TO HIMSELF AND
ALPHEUS PATTEN, OF SAME PLACE.

Letters Patent No. 63,171, dated March 26, 1867; antedated March 13, 1867.

IMPROVED KNIFE AND WATCH-KEY COMBINED.

The Schedule referred to in these Letters Patent and making part of the same.

TO ALL PERSONS TO WHOM THESE PRESENTS SHALL COME:

Be it known that I, EDWARD Q. NORTON, of Bangor, in the county of Penobscot, and State of Maine, have invented a new and useful Improvement in Pocket-Knives and Watch-Keys, and do hereby declare the same to be fully described in the following specification, and represented in the accompanying drawings, of which—

Figure 1 is an edge view, and

Figure 2 a longitudinal section of a pocket or penknife provided with my invention.

In place of a blade to the handle of the knife, and from the head from which the blade usually projects, I extend a watch-key, and I arrange across the blade-receiving recess of the handle, and so as to be against or close to the open end of the said key, a partition or its equivalent, the object of such being to prevent dirt or extraneous matters from getting into the bore of the key.

In the drawings, A represents an ordinary pocket or penknife, of which a is the handle, and b, &c., the blades. In the place of a blade I arrange a watch-key, B, formed with a head, c, to turn on the blade-rivet d, and against a spring, e, as the head of a blade usually does. A side view of the watch-key is given in fig. 3, and a transverse section of it is represented in fig. 4. Between the head c and the pipe i of the watch-key, such key is formed with a projection, g, to receive a nail niche or groove, f, which is like that of a common knife-blade, and is for the purpose of receiving the nail of a person's thumb in order that it may be brought into action on the watch-key so as to turn it on the rivet d, and raise it out of the receiver k made in the handle, and for reception of the key, as a knife-blade may be closed or shut into the handle. Close to the end of the pipe i, when shut into the handle, is a partition, l, which goes across the blade-recess m, such partition being for the purpose as hereinbefore specified. It is well known that a watch-key, as usually carried in the pocket of a person, is one of the greatest causes of dirt being introduced into the works of a watch, for the lint and dirt of the pocket will find their way into the key, and by it be introduced into the key-hole of the watch when the key is applied thereto. By having the watch-key combined with a handle as a common penknife blade usually is applied thereto, we can wind a watch with such combination much easier, and with less liability of injury to it or to the key, than we can by a key alone as ordinarily constructed, and by having the handle provided with the partition or its equivalent to cover the mouth of the key when shut into the handle, we prevent the entrance of dust or dirt into the said mouth.

I claim, as a new article of manufacture, the aggregation of the penknife-blade and watch-key in one handle, as set forth.

E. Q. NORTON.
